UNITED STATES PATENT OFFICE.

WALTER EDWIN TRENT, OF WASHINGTON, DISTRICT OF COLUMBIA, ASSIGNOR TO TRENT PROCESS CORPORATION, OF WASHINGTON, DISTRICT OF COLUMBIA, A CORPORATION OF DELAWARE.

PROCESS OF DISTILLING OIL IN PRESENCE OF COMMINUTED CARBONACEOUS FUEL.

Application filed November 4, 1920. Serial No. 421,715.

The invention relates to a process for treating oils mixed with finely comminuted carbonaceous material.

It is an object of the invention to crack 5 oils and recover the same in a form having a higher light volatile content and to accomplish this at temperatures below those employed in the present cracking processes. This is made possible by having the hydro- 10 carbon oil filmed over the surfaces of the finely comminuted coal or other carbonaceous material.

It has been discovered that oils when mixed with coal can be vaporized and condensed 15 at temperatures lower than the temperature necessary to distill oil itself, and it has also been found that the oil after this treatment, has an increased percentage of gasoline and light oil fractions.

20 The comminuted carbonaceous material may be coal, anthracite, bituminous or lignite, and pulverized coke, although it is preferable to use a comminuted fuel with a high hydrocarbon content.

25 It has also been found that the volatile content of the coal pulverized to this fine degree when filmed with oils, will distill at a lower temperature than the coal when treated by itself, and will likewise produce 30 an oil having an increased yield of low boiling fraction oil.

In application Serial Number 363,797, I disclose a process of purifying materials. This case relates to forming a fuel amalgam 35 of oil and finely divided carbonaceous content of coal, from which amalgam water and impurities are rejected. In application, Serial Number 361,230, I disclose the formation 40 of this fuel amalgam and the recovery therefrom of the oil used in making the amalgam and further collecting the volatile oils of the finely divided coals. In carrying out the practice of distilling this fuel amalgam, it was observed that the oils, in addition to being recovered, were recovered in 45 a new condition, that of having a much higher gasoline and light oil fraction than when first used to form the amalgam. It was also observed that the fuel amalgam 50 distills at lower temperatures than either the oil or coal when either is distilled by itself, and third, that the fuel residue can be

produced either as dry carbonized fuel powder or coke without having any sticky or binding hydrocarbon residue from the oil. 55

In carrying out the process for an increased yield of light oils from both oil and coal, the oil and coal, in the form of an amalgam, or otherwise, will be continuously introduced to a distilling retort. If the operation, however, is carried on for the beneficiation of oils alone, then the same comminuted coal particles can be used repeatedly in combination with fresh supplies of hydrocarbon oils that are to be treated, as the 60 mere presence of comminuted carbon in the oil while it is undergoing treatment, results in the production of a lighter grade hydrocarbon oil. 65

This process is not in any sense one of 70 fractionating the lighter hydrocarbon of the oil, and leaving the heavier hydrocarbons with the carbons. The oil is either completely distilled, or is so cracked that any 75 carbon residue remaining is in the form of dry dust, or powder, which is collected with the carbonized particles.

The invention therefore contemplates the distillation of coal and oil for the recovery 80 of light oils at low temperatures with increased yields, it also being an object of the process to carry on this distillation and avoid leaving as a residue any sticky or adhesive semi-liquid hydrocarbon either from 85 the oil or the coal, but to substantially convert them to hydrocarbon oils for several purposes. First, to obtain a maximum yield of oil of a light and higher grade quality, and second to produce a carbon product free 90 from binding substances so that the carbon, after treatment, is collected as fine carbonized particles, approximately the same size or smaller than were mixed with the oil. It has been found that by distilling such a 95 mixture and stirring or agitating the same during distillation at temperatures not to exceed 350° C., the fixed carbon residue is collected in the form of fine powder, which is desirable for use for pulverized firing. This is true, even in the case of coking coals, which under ordinary conditions, when distilled alone, will form a coke instead of 100 powder. Of course if a coke residue is required, this can be obtained by increased

temperature either with or without agitation.

In the accompanying drawings I have shown a retort for conducting my process 5 in a continuous manner, in which Figure 1 illustrates a view of the apparatus with parts in section.

Figure 2 is a detail view of the internal 10 rotating drum with one of its rabbles in section.

Figure 3 is a detail view; and,

Figure 4 is a view of the condensing and recovering apparatus.

Referring now more particularly to the 15 drawings, wherein like reference characters indicate corresponding parts, the numeral 1 designates a retort, which may have a casting composed of any suitable material sufficient to resist the necessary heat temperatures, and having a hopper 2 communicating therewith through which material is introduced to the retort. The hopper is provided with a feed conveyor 3, rotated by means of meshing gears 4 and 5, operating through 20 the medium of the gear 6, chain 7, and gear 7' on shaft 7^a, which shaft is driven by any suitable source of power by the gear 8, driven by the pulley 9.

Arranged within the retort 1 and spaced 30 from the outer wall thereof is a tube 10 preferably of cylindrical form, and providing between the walls 1 and its outer surface a heating jacket 11. The cylindrical tube receives a hollow rotating shaft 12 having 35 bearings 13 and operated by the pulley 9 hereinbefore described. This shaft carries a series of paddles or rabbles 15 arranged thereon spirally, the paddles being hollow and having cavities 16 therein receiving a heat producing medium, such as products of 40 combustion or steam. The paddles are disposed at a slight pitch, as clearly shown in Figure 1, for the purpose of agitating and slowly moving the material introduced to 45 the retort forwardly for a purpose which will later appear.

The retort is heated by products of combustion produced from burning a combustible mixture introduced to the interior of 50 the hollow rotating shaft 12 by the burner 16'. The products passing through the shaft and into the cavities 16 of the paddles 15 are then conveyed through the conduit 17 in communication with the shaft to the 55 jacket 11 disposed around the tube. The heated products then pass forwardly giving off their heat to the material undergoing treatment adjacent the rotating shaft 12, and then into the jacket 11 so as to heat the 60 exterior of the tube 10, the products finally discharging through the conduit 13'.

In following my process, the material undergoing treatment, which may be comminuted coal and hydrocarbon oil in proper 65 proportions are introduced to the hopper

2 for delivery to the interior 11 of the tube 10. Instead of raw coal, I may employ the purified carbonaceous content of coal in a finely divided state, which is a product of the process disclosed in my copending application Serial No. 363,797. From this hopper the mixed material is conveyed to the interior of the tube 10 which constitutes the treating zone and the shaft 13 revolved. The maximum temperature of the tube is 70 maintained at approximately 300° to 350° C., and the material passed through the retort by the action of the rabbles 15 is maintained in a constant state of agitation 75 and subjected to a destructive distillation 80 during its passage. If the coal containing a hydrocarbon content is distilled with the oil, the vapors from both coal and oil pass out through the discharge pipe 18 into a condenser 19, while the carbon residue which consists of dry carbonized particles or powder 85 is discharged to the conduit 20. This residue is free of sticky, oily substances, which would tend to form a binder for the carbonaceous particles, so that these carbonaceous 90 particles, when discharged are in their original state of subdivision.

The vapors entering the condensing chamber 19 undergo condensation by reason of the cooling action due to the surrounding of 95 this chamber by water or the like, introduced to a container 21 through a feed pipe 22, and discharged through a pipe 23. The condensed oils, tar and the like in the chamber 19 are collected through the pipe 24, 100 while the uncondensed vapors pass on through a pipe 25 in the condensing coils 26 disposed within a condensing chamber 27, and then to a third condensing chamber 28 surrounded by the water containing receptacle 29 having feed and discharge pipes 30 and 31 respectively. In this chamber the 105 condensable vapors are condensed and recovered through the collecting pipe 32 in the form of oils, tar, etc. It will be appreciated 110 that some of the constituents removed from the coal and oils are in the form of fixed gases and these fixed gases pass on from the condensing chamber 28 through the pipe 33 into the scrubber 34, which may be of the 115 usual type passing through this scrubber and then through a pipe 35 into a second scrubber 36, being finally discharged through a pipe 37 to a suitable container for 120 subsequent treatment or use. The scrubber removes any tars and oils which may be 125 carried by the fixed gases and these substances are collected from the scrubbers 34 and 36 by the pipes 38.

As has been previously stated, I have discovered that where hydrocarbon oils are distilled in the presence of comminuted coal, say in the proportion of 1 part oil by weight to 2 parts coal by weight, the condensed oils are in a form having a higher 130

light volatile content than the oil before treatment, and also the quantity of oil is increased.

I have also discovered that when hydrocarbon oils are distilled in the presence of comminuted coal, the vaporization of the volatiles takes place at considerably lower temperature than when the volatile content of either of the material is volatilized separately. I have successfully treated the material at a temperature of 350° C., which results in a cracking of the oils and the volatiles of the coal, leaving dry carbonized particles free of any oily or binding residue.

It will be observed that the material passing through the retort does not come directly in contact with the heating gases or flames, but that the heat is imparted to the materials indirectly or by conduction. The products of combustion pass through the central tube 12 and jacket 11, but never directly come in contact with the material undergoing treatment.

Having thus described the invention what I claim is:

1. A continuous process for the distillation of comminuted coal and hydrocarbon oil intermixed in such proportions as to provide a mass of plastic consistency, consisting in continuously advancing such mixture through a distilling zone, in mechanically agitating the material while the same is advancing through the heating zone, in heating the mixture while passing through said zone by heating gases maintained out of direct contact with the advancing materials,

in separately discharging the evolved gases from such material and the residue at the same end of the heating zone, and in maintaining the temperature throughout the heating zone sufficiently low to prevent a substantial fusion of the residue particles and to permit a substantial cracking of the evolved volatiles.

2. The method of distilling a plastic material consisting of oil and pulverized coal of a plastic consistency, consisting in continuously advancing such material through a retort, in mechanically agitating the material while the same is traveling through such retort, in heating the material to a distilling temperature by the indirect application of heating gases passing through the retort, and in separately discharging the evolved gases from such material and the residue after passage through the retort.

3. A continuous process for distilling materials, consisting in introducing a plastic mass of coal and oil to a distilling zone, in passing in a closed conduit heating gases through said zone, in continuously advancing around the surface of the closed conduit the plastic mass of coal and oil to absorb heat radiating through the walls thereof to vaporize the volatiles and produce a carbonized residue, in agitating the material during its travel around such conduit, and in separately discharging the evolved volatiles and the residue from treatment in the retort.

In testimony whereof I affix my signature.

WALTER EDWIN TRENT.
